US0D1034531S

(12) **United States Design Patent** (10) Patent No.: **US D1,034,531 S**
(45) Date of Patent: ** Jul. 9, 2024

(54) **MONITOR STAND**

(71) Applicant: **Xiao Chen**, Ningbo (CN)

(72) Inventor: **Xiao Chen**, Ningbo (CN)

(**) Term: **15 Years**

(21) Appl. No.: **29/848,973**

(22) Filed: **Aug. 8, 2022**

(51) LOC (14) Cl. **14-03**

(52) U.S. Cl.

USPC **D14/217**

(58) **Field of Classification Search**

(57) **CLAIM**

The ornamental design for a monitor stand, as shown and described.

DESCRIPTION

FIG. 1 is a perspective view of the monitor stand showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line in the figure drawings represents unclaimed environment only and forms no part of the claimed design.

1 Claim, 8 Drawing Sheets
